UNITED STATES PATENT OFFICE.

CHARLES C. SPENGLER, OF ROCKFORD, ILLINOIS, ASSIGNOR TO AUTOMATIC PENCIL SHARPENER COMPANY, OF CHICAGO, ILLINOIS, A CORPORATION OF NEW YORK.

PENCIL-SHARPENER.

1,280,323.

Specification of Letters Patent.

Patented Oct. 1, 1918.

Application filed December 2, 1915. Serial No. 64,632.

To all whom it may concern:

Be it known that I, CHARLES C. SPENGLER, a citizen of the United States, residing at Rockford, in the county of Winnebago, State of Illinois, have invented certain new and useful Improvements in Pencil-Sharpeners, of which the following is a specification.

My invention relates to pencil sharpeners, and particularly to that type of pencil sharpeners in which the sharpening operation is performed by means of rolls provided with helically-disposed cutting edges between which rolls a pencil may be inserted.

It is an object of my invention to provide such a pencil sharpener with means for guiding and centering pencils of different sizes in the space between the cutting rolls.

A further object of the invention is to provide the shavings receptacle with a locking key whereby it may be readily and easily secured in position on the sharpener or removed therefrom as desired.

A further object is to mount the guide-reducing member upon the locking key and carry it to and from the cutting axis by movement of the key; also to accomplish this without withdrawing the key from locking relation.

These and other advantages of my invention may be more readily understood by reference to the accompanying drawing, which shows a preferred embodiment of my invention, and in which—

Figure 1 is a side elevation of a pencil sharpener embodying the invention, a part thereof being broken away and a part being shown in section;

Fig. 2 is a front elevation showing one member of the device in alternative position in dotted lines; and

Fig. 3 is a front elevation showing such member in still another position.

The pencil sharpener in connection with which the invention is illustrated comprises a base 1, which may be suitably secured to either a horizontal or vertical surface. A support 2 is suitably secured to the base 1, and is provided with a bearing 3, in which a revoluble cutter frame 4 is journaled. The cutter frame 4 carries the usual rolls 5 formed with helical cutting edges and arranged in the usual manner so that on rota-

tion of the frame by the crank 6 the rolls 55 may be revolved around the axis of the cutter frame, and also upon their own axes. The outer end of the cutter frame is provided with an aperture 7, through which a pencil may be inserted, and by which the pencil will be centered in the space between the cutter rolls 5. A peripheral groove 8 is formed in the outer end of the cutter frame. The support 2 is provided with a head 9 having a peripheral shoulder 10.

A shavings receptacle, which may preferably be formed with either mica or metal sides and top 11 secured between a front plate 12 and a back plate 13 united by bars 14, is formed with a back opening whose edge is designed to engage the shoulder 10 and with a flanged opening 15 in its front wall 12, which is designed to embrace the end of the cutter frame 4. The front wall 12 of the receptacle is preferably formed 75 with oppositely disposed ears 16.

A plate member 17 is slidably and adjustably secured against the front wall 12 of the receptacle preferably by forming the plate with a slot 18 through which extends 80 a screw 19 threaded into the front wall 12. At its sides the plate 17 is formed with fingers 20, while between the fingers it is formed with the central portion 21 forming a guide-reducing member, in which is an 85 opening 22 smaller in size than the pencil-receiving aperture 7 in the end of the cutter frame 4, said guide reducing member having a convex depression that causes it to seat slightly within the enlarged guide opening and thereby center the guide-reducing opening and hold it against unintentional displacement. Thus the plate constitutes a key for locking the receptacle to the frame, and this key is carried by the receptacle, and 95 since its fingers engage the frame through a peripheral groove, it is adapted to maintain its interlocking relation at different angular positions of the receptacle.

In normal operation the shavings receptacle is positioned on the cutter frame, and is held there by securing the plate 17 in the position shown in dotted lines in Fig. 2. In this position of the plate the fingers 20 engage the peripheral groove 8 in the cutter frame and effectually prevent removal of the receptacle, while at the same time the aperture 7 in the cutter frame 4 is fully

- exposed to allow the insertion of a pencil of the same size as the aperture. If it be desired to use the sharpener for operating on pencils of smaller diameter, the plate 17 is 5 slid and adjusted to the position shown in full lines in Fig. 2, so that the opening 22 in the central portion of the plate is moved into position concentric with the aperture 7 and so that it will serve to receive and center a pencil of smaller diameter in the space 10 between the cutter rolls 5. The plate 17 slides behind the ears 16, which serve to guide it and hold it in position. If it be desired to remove the receptacle from the 15 sharpener, the plate 17 is slid to the position shown in Fig. 3, in which the fingers 20 are disengaged from the peripheral groove 8 in the end of the cutter frame 4, so that the receptacle may be bodily removed.
- 20 From the foregoing it will be seen that the key has three positions, namely, one unlocking position and two locking positions, in one of which latter positions the guide-reducing member 22 coincides with the cutting axis and is adapted to hold the locking key in such position, while in the other the guide is removed from alinement with the cutting axis and leaves the opening enlarged 25 to receive a larger pencil and the receptacle 30 still in locked position.

It will be apparent to those skilled in the art that many changes could be made in the detailed construction of the parts which I have described without departing from the 35 spirit or scope of my invention as defined in the appended claims.

What I claim is:

1. In a pencil sharpener, a support, a cutter carried by the support and adapted to 40 admit a pencil in the line of the cutting axis, a receptacle removably mounted on the support, a locking key carried by the receptacle movably interlocked with the cutter, and a guide-reducing member on said 45 key and carried thereby into and out of alinement with the cutting axis.

2. In a pencil sharpener, a support, a cutter carried by the support and adapted to admit a pencil in the line of the cutting 50 axis, a receptacle removably mounted on the support, a locking key carried by the receptacle having two positions in which it is interlocked with the cutter, and a guide-reducing member carried on said key and 55 carried thereby from one of said positions in which it is in alinement with the cutting axis to the other of said positions in which it is out of such alinement.

3. In a pencil sharpener, a support, a cutter carried by the support and adapted to 60 admit a pencil in the line of the cutting axis, a receptacle removably mounted on the support, a locking key carried by the receptacle movably interlocked with the 65 cutter, and a guide-reducing member on said

key and carried thereby into and out of alinement with the cutting axis, said guide-reducing member being adapted to engage in its alined position and retain the locking key against movement. 70

4. In a pencil sharpener, a support, a cutter carried by the support and adapted to admit a pencil in the line of the cutting axis, a receptacle removably mounted on the support, a locking key carried by the receptacle movably interlocked with the cutter, and a guide-reducing member on said key and carried thereby into and out of alinement with the cutting axis, engagement of the key with the cutter being through the 80 medium of an annular groove in the latter, whereby the key may inter-lock with the cutter in different angular positions of the receptacle. 75

5. In a pencil sharpener, a support, a cutter carried by the support and adapted to admit a pencil in the line of the cutting axis, a receptacle removably and rotatively mounted on the support, a locking key carried by the receptacle movably interlocked with the cutter, and a guide-reducing member on said key and carried thereby into and out of alinement with the cutting axis, engagement of the key with the cutter being through the medium of an annular groove 90 in the latter, whereby the key may inter-lock with the cutter in different angular positions of the receptacle. 85

6. A pencil sharpener comprising a support, a cutter having an opening to receive a pencil in the line of the cutting axis, a plate mounted to slide in a line intersecting the cutting axis, and a guide-reducing member on said plate, carried thereby to and from position in alinement with the cutting 100 axis; said guide-reducing member being depressed to cause it to seat in the opening of the cutter and thereby retain it in alinement with the latter. 105

7. In a pencil sharpener, the combination 110 of a support; a cutter frame journaled in the support and having a pencil-receiving aperture; a receptacle removably positioned against the support; and a member secured to the receptacle and securing the receptacle in position, said member having an opening of different size than said aperture and being adjustable alternately to bring said opening into position concentric with said aperture or to a position to release said receptacle. 115

8. In a pencil sharpener, the combination 120 of a support; a cutter frame journaled in the support; a receptacle removably positioned on the frame beyond the end thereof, said end having a pencil-receiving aperture; and a member secured to the front of the receptacle and engaging the end of the frame, said member having an opening smaller than said aperture and being ad- 125

justable alternatively to bring said opening into position concentric with said aperture or to a position to disengage the frame.

9. In a pencil sharpener, the combination
5 of a support; a cutter frame journaled in the support; a receptacle removably positioned on the frame beyond the end thereof, said end having a pencil-receiving aperture and a peripheral groove; and a member
10 slidably secured to the front of the receptacle and having fingers engaging said groove, said member having a central portion formed with an opening smaller than said aperture, the member being adjustable
15 alternatively to bring said opening into position concentric with said aperture or to a position to disengage said fingers from said groove.

10. In a pencil sharpener, the combination

of a support; a cutter frame journaled in 20 the support; a receptacle carried by the cutter frame and removably positioned against the support; and means for locking the receptacle in position, on the cutter frame at a point remote from the support.

25

11. In a pencil sharpener, the combination
of a support; a cutter frame journaled in the support; a receptacle removably positioned on the frame; and a member movably secured to the receptacle and adapted to engage the cutter frame at a point remote from the support to lock the receptacle in position.

30

In witness whereof, I hereunto subscribe my name this 30th day of November, A. D. 35
1915.

CHARLES C. SPENGLER.
